UNITED STATES PATENT OFFICE.

LEWIS D. COE, OF LEADVILLE, COLORADO, ASSIGNOR OF ONE-HALF TO
JOSEPH A. LAMPING, OF SAME PLACE.

AMALGAMATOR.

SPECIFICATION forming part of Letters Patent No. 581,611, dated December 25, 1894.

Application filed January 16, 1894. Serial No. 497,051. (No model.)

To all whom it may concern:

Be it known that I, LEWIS D. COE, of Leadville, in the county of Lake and State of Colorado, have invented a new and Improved 5 Amalgamator, of which the following is a full, clear, and exact description.

The object of the invention is to provide a new and improved amalgamator, which is comparatively simple and durable in construction, very effective in operation, and arranged to save all the precious metals contained in the material and to permit of conducting the operation without interruption.

The invention consists principally of a mercury well connected with a supply pipe and into which extends a riffle discharge channel.

The invention also consists of certain parts and details, and combinations of the same, as will be hereinafter described and then pointed 20 out in the claims.

Reference is to be had to the accompanying drawings, forming a part of this specification, in which similar letters of reference indicate corresponding parts in all the figures.

25 Figure 1 is a sectional side elevation of the improvement on the line 1—1 of Fig. 2. Fig. 2 is a sectional plan view of the same on the line 2—2 of Fig. 1; and Fig. 3 is a transverse section of the same on the line 3—3 of Fig. 2.

30 The improved amalgamator is provided with a suitably-constructed vessel or well A supported in a framework B, and provided in one side with a supply pipe C containing a valve C', and opening into a vessel D, containing mercury, to charge the said well A from time to time with the necessary amount 35 of mercury. On one side of the well A is arranged a glass gage E, to indicate the amount of mercury contained in the well. Into the

40 well A and near the bottom of the same extends a supply pipe F, through which the material to be treated and containing precious metal, together with water, is passed into the mercury contained in the well A. The inner

45 spout-like end of the supply pipe F is covered by a screen G, so that the material passes in a finely divided state into the mercury contained in the well. The pipe F is held in a boss A' forming part of the well A, and into 50 the said boss extends the pipe H, formed at its upper end with a flaring mouth H' con-

nected with the bottom of a chute I, through which the material is washed from the mills, screened from placer mining sluices or other places, and containing fine gold or other precious metals that are so fine and light in weight that they float, and cannot be amalgamated on plates or caught by other riffles or devices, and by this device forced directly into the mercury. 55

In the bottom of the chute I, directly over the flaring mouth H' is arranged an opening covered by a screen I', so that only the finer material, together with the water, passes through the said screen into the mouth H' and pipe H, to finally pass into the pipe F and through the screen G into the mercury in the well A. A valve J arranged on the under side of the bottom of the chute I serves to open and close the screen opening at the 60 mouth H', so as to regulate the amount of water and material passing from the chute I into the pipe H. The latter extends such a distance upward as to produce a sufficient hydrostatic pressure of the water passing 65 through the pipe, to force the material through the screen G into the mercury contained in the well A. 70

The forward end of the chute I is provided with an outlet K, down which falls the coarser, 80 heavier material, rock and waste, to the same current of water beyond the amalgamator, passing along the chute I over the screen I'. The well A is provided with an outlet channel A² formed with the bottom parts A³ and A⁴, 85 of which the part A³ is inclined downwardly and inwardly into the well, so that the mercury contained in the well extends over the said bottom part A³ onto a riffle frame L, as plainly shown in Fig. 1. The mercury in the 90 well A forms a mercury bottom for the part A³ of the well outlet A², so that the fine particles of mercury which may become separated can more readily come in contact with the main body of mercury and run back into 95 the well. The other bottom part A⁴ leads outward and downward to carry off the tailings, as hereinafter more fully described.

The riffle frame L is provided with two longitudinally-extending side beams L' and L² connected with each other by transverse riffles L³ slanting upwardly, as plainly indi-

cated in Fig. 1. The side beams L' and L^2 are fastened on the top surface of the part A^4 and to the sides of the channel A^2 and then extend inwardly into the well, as plainly indicated in Fig. 1, the said side beams being curved downward, as will be readily understood by reference to the said Fig. 1.

In order to draw off the amalgam from the well A, I arrange in the bottom of the latter 10 a pipe N, provided with a valve N' and discharging into a vessel O, set below the said pipe, as plainly shown in Figs. 1 and 3. On the lower end of the pipe N is held a cover N² for the vessel O to prevent the amalgam 15 from splashing over the top of the said vessel. A suitable locking device is provided to temporarily lock the vessel O and cover together, to prevent dishonest parties from tampering with the contents of the vessel.

10 The operation is as follows:—The well A is first filled with mercury to such an extent that when the hydrostatic pressure is applied the mercury will rise in the well to a sufficient height to form a mercury bottom to the part 20 A^3 of the outlet A^2 and consequently reaches the inner end of the riffle frame L. The valve J is then opened so that the material washing down the chute I passes through the screen I' into the pipe H and is washed down the 25 same by the accompanying water. The material is forced through the screen G in a finely divided state by the hydrostatic pressure of the column of water in the pipe H, so that the material in the finely divided state 30 passes into the mercury contained in the well A and in rising therein brings its precious metal in contact with the mercury so as to combine with the same, while the tailings pass upward onto the surface of the mercury to pass 35 over the several riffles L³ into the channel A^2 and finally down the inclined bottom A^4 to the outside of the amalgamator. Now, it will be seen that any precious metals contained in the material, after passing through the mercury 40 and coming in contact with the riffles L³, will be separated from the tailings and brought into contact with the mercury, to be taken up by the latter. The amalgam settling in the bottom of the well A can be drawn off from 45 time to time by the operator opening the valve N' in the pipe N so that the amalgam passes into the vessel O. The operator after having drawn off the amalgam closes the valve N' and opens the valve C' so as to again charge the 50

well A with mercury from the supply vessel D. 55 By this arrangement the supply of material and water through the chute I need not be stopped, and thus the operation can be carried on continuously in the manner above described. The well A, as well as part of the 60 channel A^2 is preferably covered by a hinged lid A⁵ as shown in Figs. 1 and 3.

Having thus fully described my invention, I claim as new and desire to secure by Letters Patent—

65 1. In an amalgamator, the combination with a mercury well having an outlet channel, of a riffle frame secured in the outlet channel and projecting into the well, substantially as and for the purpose set forth.

70 2. In an amalgamator, the combination with a mercury well having an outlet channel, of a material supply pipe projecting into the well, near the bottom thereof, a screen on the inner end of the said pipe, and a riffle frame secured in the outlet channel and projecting into the well, substantially as described.

75 3. In an amalgamator, the combination with a mercury well having an outlet channel, the bottom portion A^3 of which inclines downwardly and inwardly, and the portion A^4 downwardly and outwardly, of a riffle frame secured to the part A^4 of the bottom of the channel and projecting over the part A^3 into the well, substantially as described.

80 4. In an amalgamator, the combination with a mercury well having an outlet channel, of a chute above the well, and having a valved opening in its bottom and a supply pipe leading from the opening in the bottom of the 90 chute to the mercury well near the bottom thereof, and having its inner end projecting a short distance into the well and covered by a screen, substantially as described.

85 5. In an amalgamator, the combination with a mercury well having an outlet channel, of a chute above the well, a supply pipe leading from an opening in the bottom of the chute to the well and projecting into the same near the bottom thereof, a screen covering the end 100 of the supply pipe projecting into the well, and a riffle frame secured to the bottom of the outlet channel and projecting into the well, substantially as described.
